UNITED STATES PATENT OFFICE.

C AXEL CARLSON, OF ROCKFORD, ILLINOIS.

OVERWIND-PREVENTING MEANS FOR SPRING-OPERATED DEVICES.

Application filed January 3, 1927. Serial No. 158,442.

This invention relates to spring operated devices generally and is particularly concerned with the provision of a simple and practical form of means for preventing overwinding of the power spring.

According to the present invention, I provide means for positively limiting the number of winding turns of the winding stem or arbor to prevent overwinding and avoid danger of breaking the spring or placing other parts of the mechanism driven thereby under an overload.

As will presently appear, a movable part is provided arranged to move progressively toward a limit position during the winding operation so as to prevent winding beyond a certain predetermined extent.

The invention is illustrated in the accompanying drawings, wherein—

20 Fig. 1 is a view of a watch, the cover plate of which is removed to disclose the parts visible at the top plate, the present invention being employed in connection with the winding wheel;

25 Fig. 2 is an enlarged sectional detail taken on the line 2—2 of Fig. 1 to show the relationship between the winding wheel and the overwinding preventing means of my invention;

30 Fig. 3 is a view taken on the line 3—3 of Fig. 2 looking in the direction of the arrows;

Fig. 4 is a view similar to Fig. 3 with the outermost plate removed to disclose the sliding plate; and

35 Fig. 5 is still another similar view with the sliding plate removed to show the inner plate with its spiral groove by means of which the sliding plate is moved back and forth from one limit position to another in the unwinding and winding of the main spring.

The same reference numerals are applied to corresponding parts throughout the views.

The present invention as stated before, contemplates application generally to all spring operated devices such as phonographs, clocks and watches, mechanical toys and the like; in short, wherever it becomes desirable or expedient to prevent overwinding of the power spring. For the purposes of the present description, I have shown the application of my invention to use in the works of an ordinary watch for limiting the winding of the main spring. The watch shown

55 at 6 is, for the most part, of the usual construction having a top plate 7 with a

winding wheel 8, and crown wheel 9. The stem 10 has the usual connection with the crown wheel to turn the winding wheel to wind the main spring 11 (Fig. 2). One end 60 of the main spring is fixed, as at 12, to the stem or arbor 13 bearing the winding wheel 8, while the other end is suitably fixed to the main wheel 14. The main wheel meshes with the usual center pinion 15 to transmit 65 the power of the main spring to the watch works. The winding wheel is, of course provided with the usual recoil click (not shown). This brief description will suffice to introduce the parts with which the present 70 invention is concerned. As will presently appear, my invention provides for the limiting of the number of winding turns of the winding arbor 13 so as to prevent overwinding of the main spring 11.

According to the present invention, three plates, designated 16, 17, and 18 are provided, the plate 16 having the hub portion 19 receiving the arbor 13 with a drive fit so that the plate 16 turns with the arbor 80 during winding. The plate 18 has a rim portion 20 making a drive fit about the rim 21 projecting from the side of the main wheel 14 to encase the main spring 11. The plate 18, therefore, turns with the main wheel 85 14 and is stationary relative to the plate 16 during winding and turns relative to the latter during unwinding. The plate 17 is received in a recess 22 provided on the inner side of the plate 16 and is arranged to have 90 95 sliding movement back and forth between the two plates during winding and unwinding. As shown in Fig. 4, the plate 17 is of a double arcuate form so as to fit within the rim of the depression 22 at both ends of its travel, that is, in its position corresponding to the completely wound condition of the spring and that corresponding to the unwound condition of the spring. The plate 17 is guided for rectilinear movement relative to the plate 16 by lugs 23 projecting from the plate 17 and received in radial slots 24 provided in the plate 16. A slot 25 is provided in the plate 17 between the lugs 23 to permit movement of the plate 100 105 relative to the arbor 13. An arcuate lug 26 is provided on the inner side of the plate 17 to fit in a spiral groove 27 cut in the outer face of the plate 18. In the turning of the winding arbor, the plate 16 is arranged to turn the plate 17 with it and cause the lug 26 to travel from a limit position at one

end of the spiral groove 27 toward the other end of said groove. The progress of the lug 26 in the groove 27 is reflected in the travel of the lugs 23 toward the ends of the slots 24. I prefer, however, to make the slots 24 of sufficient length so that the lugs 23 will approach no closer to the end thereof than about as shown in Fig. 3, thus making it unnecessary to work to such close limits in the cutting of the spiral groove 27 as would otherwise be required if the lug 26 had to come to the end of the groove 27 at exactly the same time that the lugs 23 reached the ends of the slots 24. In the present case, four and one-half turns of the arbor 13 will suffice to carry the lug 26 from one end of the spiral groove 27 to the other end by reason of the fact that the groove has four and one-half turns therein, as shown in Fig. 5.

In operation, the turning of the winding stem 10 of the watch, or other spring operated device, turns the plate 16 and causes the lug 26 of the plate 17 to travel from one end of the spiral groove toward the other end, by reason of the fact that the plate 17 is held for rotation with the plate 16 by the engagement of the lugs 23 in the slots 24. When four and one-half turns of the arbor have been completed, or whatever predetermined number is provided for, the lug 26 comes into engagement with the end of the groove 27 and positively prevents further turning of the arbor. It is, therefore, impossible to overwind the spring and the danger of breaking the spring or placing any of the driven parts under an overload is avoided. The operator is definitely aware of the fact when he has wound up the spring to the proper extent.

During unwinding, it is obvious that the reverse from the operation above described will occur. That is, the plate 16 will remain stationary while the plate 18 will turn gradually with the main wheel 14 in the unwinding of the spring and, therefore, cause the lug 26 to move progressively from the limit position above referred to back toward its initial position. In the drawing the parts appear in the relative positions occupied thereby when the main spring is substantially unwound.

It is believed the foregoing description conveys a clear understanding of the advantages of my invention and of its many possible applications. While the present description has made reference to one particular embodiment, it should be understood, as stated above, that the invention is capable of many other embodiments as will readily appear to anyone skilled in the art. The appended claims have been drawn with a view to covering all legitimate modifications, adaptations, and variations coming within the spirit and scope of the invention.

I claim:

1. An overwind prevention unit for spring operated devices, comprising three plates disposed in face to face relation, the one outside plate being connected to the middle plate by means of one or more lugs provided on the face of one plate engaging in one or more radial guideways provided on the other plate, and the other outside plate being operatively connected to the middle plate by means of a lug provided on the face of one plate engaging in a spiral guideway provided on the other plate, the one outside plate being arranged to be turned in winding and the other outside plate being arranged to be turned in unwinding and the arrival of one of said lugs at the end of its guideway in winding serving to prevent more than a certain amount of winding.

2. In a spring operated device, the combination with a winding stem, a power spring having one end thereof fixed to said stem, and a power transmitted gear having the other end of said spring fixed thereto, of means for preventing overwinding of said spring comprising a plate fixed to turn with said stem, said plate having a radial slot therein providing a guideway, a second plate guided for sliding movement on said first plate and having a portion thereof received in the slot in said first plate, and a third plate in relation to which the other two plates are movable in winding, said third plate having a spiral groove therein to provide a second guideway, said second plate having a part received in said groove whereby in the turning of said first plate said second plate is moved radially the arrival of the second plate at one end of one of said guideways serving to limit the number of turns of said stem in winding.

3. A structure as set forth in claim 2 wherein the third plate is fixed with respect to said power transmitting gear, and serves to enclose the power spring between it and said gear, the second plate being disposed between the first and third plate, and one of the latter two plates being recessed to enclose the second plate between it and the other plate.

4. In a spring operated device the combination of a winding stem, an element turned thereby in winding, another element relatively stationary during winding, and means comprising two inter-threading parts serving to limit the turning of said stem, the one part being operated by the first element and the other part being fixed with the other element.

5. An over winding prevention unit for spring operated devices comprising a pair of coaxially arranged members, the first of which is arranged to turn with a part turning during winding of the spring, and the other of which is arranged to turn with a

part turning during unwinding of the spring, the said two members being disposed in fixed spaced relations, and a third member disposed between and operatively connected with the other two members and arranged in the turning of the first member relative to the second to move progressively to a limit position where it holds the first member against further turning and thereby 10 prevents more than a certain amount of winding.

6. A device as set forth in claim 5 wherein the three members are flat plates, one of the first two having a radial slot therein and the other having a spiral groove, the third having a lug on one side engaging in the slot and a lug on the other side engaging in the groove. 15

In witness of the foregoing I affix my signature.

C AXEL CARLSON.
